UNITED STATES PATENT OFFICE.

WALTER MORRIS, OF DULWICH HILL, NEAR SYDNEY, NEW SOUTH WALES, AUSTRALIA, ASSIGNOR TO C. W. ELLIOTT LIMITED, OF ST. PETERS, NEAR SYDNEY, AUSTRALIA.

HINGE FOR VEHICLE DOORS.

Application filed January 6, 1922. Serial No. 527,303.

To all whom it may concern:

Be it known that I, WALTER MORRIS, subject of the King of Great Britain and Ireland, residing at 79 Cobar Street, Dulwich Hill, near Sydney, New South Wales, Australia, have invented new and useful Improvements in an Improved Hinge for Vehicle Doors, of which the following is a specification.

10 This invention relates to "concealed" hinges for automobile and other carriage doors, and it consists in making such hinges demountable at the knuckle, with the object that the doors may be removed from the vehicle without disturbing the fastenings by which either leaf of the hinge is fixed to the frame post and to the door stile respectively. The particular mechanical arrangement used permits the use of any 15 standard form of the boxed hanging leaf which is adapted to be inset in the frame post, with the pintle pin permanently fixed in it, and it furthermore ensures connection of the leaves through the knuckle without 20 looseners consequent on the provision for the detaching of the cranked swinging leaf from the boxed hanging leaf.

According to the present invention the eye piece of the knuckle is permanently carried 25 on the pintle pin, and is armed with a stem piece offset at right angles from its axis. In the cranked portion of the swinging leaf a hole is drilled to receive this stem piece and the end of the crank is recessed to embrace the eye piece. A nut housed in a 30 countersink in the stem hole engages the stem piece and secures the swinging leaf to the knuckle eye. This nut being secreted in the countersink, though accessible therein, is not a disfigurement and is 35 practically unobservable. When it is freed the cranked swinging leaf may be drawn off the eye stem to demount the door from the frame.

40 According to the present invention, the pintle pin is fixed in the recess of the post leaf, and the hanging leaf is mounted on the pintle pin by a knuckle which is detachably fixed in the hanging leaf.

45 In the accompanying drawings:—

Fig. 1 is a horizontal sectional view of a structure comprising a port or standing portion and a door with a hinge mounting ac-

cording to the present invention; as shown 55 the parts appear with the door closed;

Fig. 2 is a perspective view of the boxed hanging leaf;

Fig. 3 is a perspective view of the cranked swinging leaf;

Fig. 4 is a perspective view of the knuckle 60 eye with its offset stem;

Fig. 5 is a horizontal sectional view corresponding with Fig. 1 and showing the door swung open; and

Fig. 6 is a vertical sectional view on the 65 line 6—6 of Fig. 5.

The hanging leaf is of the usual boxed form shown in Fig. 2, adapted to be inset in a recess formed for it in a door post or equivalent portion 10 of a vehicle body, by means of screws inserted through the flange holes 11. 12 are holes in which the ends of the pintle pin 18 are mounted. The swinging leaf (Fig. 3) is flanged and holed at 13 for fastening screws by which it is fixed to the hanging stile of the door. The swinging leaf is cranked at 14, and the end of the cranked portion 15 is recessed at 16 to form a seating for the knuckle eye 17, through which the pintle pin 18 passes. The 70 knuckle eye 17 is armed with an offset stem piece 19 which is accommodated in a hole 20 drilled through the cranked portion 15 of the swinging leaf (Fig. 3). The outer end of the holes 20 is counterbored as shown 75 at 21 to accommodate a cap nut 22 which is adapted to be screwed on to the end 23 of the knuckle stem 19. In setting up the hinge, the knuckle 17 is set on the pintle pin 18 and the pin ends riveted over or otherwise 80 secured in the holes 12 in the hanging leaf. The swinging leaf (Fig. 3) is then set in 85 position with the knuckle stem 19 in the hole 20 and secured therein by means of the cap nut 22; the hinge then appears externally as 90 a cranked leaf concealed hinge of the conventional type, the nut being countersunk, 95 not being a cause of disfigurement. Removal 100 of the door without disturbing the hinge setting is, however, readily accomplished by removing the cap nuts 22 and then drawing the cranked swinging leaves off the knuckle stems. Any fitting or finishing work required to be done on the door may then be 105 accomplished with the greatest facility and the door finally replaced, the hinge fitting

being not at all disturbed in these operations.

What I claim as my invention and desire to secure by Letters Patent is:—

- 5 1. A concealed door hinge comprising in combination a recessed leaf adapted to be mounted in a cavity in the door post, said leaf formed with an open side and front and being closed elsewhere, and having a 10 pintle pin mounted in the recess, a T-stem extending laterally from said pintle, and a crank leaf having a flat butt plate adapted to be secured to the inner face of the door stile, there being a socket hole in the crank 15 leaf, said leaf adapted to receive the extending portion of said T-stem, and a fixing nut adapted to engage the end of said stem whereby the stem is detachably locked in the crank portion of the crank leaf.
- 20 2. In combination in a) concealed door hinge a post leaf forming a recess and being open at one side and end and closed elsewhere, a pintle pin pivoted within said post leaf and having a lateral extension which is 25 provided on its outer end with a threaded portion, and a crank leaf, said crank leaf provided with a flat portion adapted to be secured to the door and to lie in the same general plane therewith and provided with

a crank arm extension lying partially in a 30 plane parallel to that of the door and partially bent at right angles to such plane, said bent portion being adapted to be removably secured to the lateral extension of said pintle pin.

3. In combination in a concealed door hinge a post leaf forming a recess and being open at one side and end and closed elsewhere, a pintle pin pivoted within said post leaf and having a lateral extension which is 40 provided on its outer end with a threaded portion, and a crank leaf, said crank leaf provided with a flat portion adapted to be secured to the door and to lie in the same general plane therewith and provided with 45 a crank arm extension lying partially in a plane parallel to that of the door and partially bent at right angles to such plane, said bent portion being perforated to receive the lateral extension of said pintle pin 50 and to be removably secured thereon, said laterally bent portion adapted to lie against the inner side of said post leaf when the door is closed and to be stopped thereby.

In testimony whereof I have signed my 55 name to this specification.

WALTER MORRIS.
